UNITED STATES PATENT OFFICE

2,196,724

STOVE

Edwin Esson, Watertown, Mass., assignor to
Walker & Pratt Manufacturing Company,
Watertown, Mass.

Application August 25, 1939, Serial No. 291,826

11 Claims. (Cl. 126—214)

This invention relates to improvements in stoves.

The main objects of my invention are:

First, to provide an improved kitchen range which is well adapted for utilizing a plurality of different types of fuel, having a novel top contributing materially to the improved appearance as well as the operation and efficiency thereof.

Second, to provide a combination range of the type described, having provision for burning oil or solid fuel and means for concentrating the heat from the combustion thereof.

Third, to provide a combination oil or coal and gas range which has all of the sales appeal from an appearance standpoint of modern gas and electric ranges.

Fourth, to provide a range including an oil or solid fuel burner and means for concentrating the heat therefrom on the stove lids while at the same time minimizing the amount of heat lost in such an installation.

Fifth, to provide a heat concentrator adapted for association with the combustion chamber or box of an oil or solid fuel burning range to concentrate the heat therefrom on the stove lids of the range and greatly reduce heat conduction or radiation from parts of the range other than the lids.

Further objects relating to details and economies of my invention will definitely appear from the description to follow. The invention is defined in the claims.

A structure embodying the features of my invention is illustrated in the accompanying drawing, wherein:

Fig. 1 is a front perspective view illustrating the combination range in accordance with my invention, an adaptation thereof for an oil or solid burning installation being illustrated in solid lines with the necessary modifications for converting the same for a combination including gas or electric burners or heaters being indicated in dotted lines.

Fig. 1A is a fragmentary perspective view of a modified embodiment of part of the range construction illustrated in Fig. 1.

Fig. 2 is a fragmentary front elevational view partially broken away and in vertical section illustrating details of construction of the improved heat concentrator of my invention and an insert for the stove top associated therewith.

Fig. 3 is a perspective view illustrating the said heat concentrator when removed from the stove.

It is the primary purpose of the present in-

vention to provide a kitchen range suitable for either oil or solid fuel and also to have incorporated therein a number of gas or electric burners or heaters in the event they are desired. It is likewise highly desirable to provide such a range which has all of the eye appeal of modern gas and electric ranges with the economy of an oil or coal burning operation. Accordingly, I have provided a kitchen range having a one-piece top which is very neat and attractive in appearance and which may be produced very inexpensively. This top has an opening therein receiving an insert for supporting stove lid holders or, if desired, in the case of a combination type range the said one-piece top may also be suitably apertured at one side of the insert opening to receive gas burners or electric heaters. Further provision of the invention resides in the use of a novel one-piece cast heat concentrator associated with the aforesaid insert formed in a manner to concentrate the heat from an oil burner or solid fuel firepot at the stove lids or openings therefor and associated with the range top in a manner to eliminate radiation and thereby increase the economy of operation of the unit.

Referring to the drawing, the reference numeral 1 in general indicates my improved range the body of which is provided with closure 2. For example, an oven disposed centrally of the stove is closed by the closure 2 while the closure 3 conceals a storage compartment and the closure 4 affords access to an oil or solid fuel combustion chamber 5 wherein a suitable conventionally shown burner 6 (which may be either an oil burner or the grate of a solid fuel unit) is installed.

The space around the combustion chamber 5 and interiorly of the external shell or wall 7 of the range body is filled with a suitable insulating material 8.

The reference numeral 9 indicates a one-piece vitreous enameled sheet iron top which is provided with a bottom peripheral inturned flange 10 adapted to rest on a similar inturned flange 45 11 on the shell 7 as illustrated in Fig. 2. As illustrated in solid lines in Fig. 1, this top is provided with an integral vertical back piece or guard 12 and has formed in its horizontal surface a rectangular opening 13 adapted to receive 50 a suitable insert 14, which may be of cast iron, being provided with an inwardly disposed shoulder 15 surrounding this opening to support the insert. Alternatively and within the scope of my invention, if desired the top 9 may be pro- 55

vided with a further opening 16 as indicated in Fig. 1A, outlining a space for the reception of gas burners or electric heaters, which latter may be conventionally mounted within the space beneath the top, and a conventional spider-like supporting plate or grill 91 may be disposed in the opening 16. Although, as stated, the aforesaid supplemental burner opening may be provided in the top 9 when a combination type range 10 is desired, it should be understood that my invention is primarily directed to a one-piece top 9 and other structural features to be described regardless of the type or number of heaters embodied in the range.

15 The insert 14 is formed with an appropriate number of burner openings 18, four being shown in the present embodiment. As illustrated, the combustion chamber 5 has an offset at one side at 19 and a smoke discharge opening or flue 20 20 is formed at the rear of the offset. The combustion chamber or housing has an open top which is covered by the heat concentrator 21 illustrated in Fig. 3.

This concentrator is in the form of a casting 25 having an annular down-turned flange 22 adapted to fit over the upper edge of the walls of the chamber 5 and support the concentrator in operative position. Upwardly tapered open ended concentrator domes 23 are provided in alignment with the insert burner openings 18, these domes terminating slightly below the upper surface of the insert 18 and being adapted to telescopingly receive the annular stove lid holders 24 which also engage the insert 14 in the manner 30 illustrated in Fig. 2. The usual stove lids 25 are received by the holders 24 in conventional manner. The holders and lids are disposed to lie substantially flush with or only slightly above the plane of the range top.

40 After assembly of the concentrator 22 on the chamber or housing 5 in the manner described, the space surrounding the various domes 23 is filled with the insulating material 8 so as to completely insulate these domes from one another and the remainder of the range, with the 45 result that the efficiency of the unit is greatly increased, the only radiation occurring at the stove lids. At the same time, these domes 23 concentrate the heat from the burner 6 while 50 serving as supports for the stove lids and holders.

55 In Fig. 1, a suitable door for lighting the burner 6 is generally indicated by the reference numeral 26.

The foregoing construction is one which is efficient in its combustion and very attractive in appearance so as to have considerable sales appeal. It is furthermore exceedingly economically produced either in the form of a combination range or one for straight oil or wood construction. I have illustrated and described my improvements in an embodiment which is very practical. I have not attempted to illustrate or describe other embodiments or adaptations as it is believed this disclosure will enable those skilled in 65 the art to embody or adapt my improvements as may be desired.

Having thus described my invention, what I claim as new and desire to secure by Letters Patent is:

70 1. In a range for burning solid fuel or oil having an open top combustion chamber and a fuel burning unit in said chamber, said range having other heating means in addition to said unit, a top for said range comprising a one-piece vitreous 75 enameled sheet iron member having an inturned

flange resting on the outer shell of said range, said member having a flat top and an integral upturned back piece, said top having an opening therein over said combustion chamber surrounded by an inturned shoulder, a cast iron insert adapted to rest on said shoulder in said opening and having stove lid openings therein, a cast iron concentrator member having means for supporting the same on said combustion chamber to cover the latter, said concentrator having a plurality of spaced upwardly tapered and opening concentrator domes disposed in vertical alinement with the respective openings in said insert, insulating material surrounding said domes and insulating the same from one another and the rest of the range, stove lid holders telescopingly received by said domes and engaging said insert around said openings therein, and stove lids disposed in said holders and covering said domes.

2. In a range having an open top combustion chamber, a top for said range comprising a one-piece vitreous enameled sheet iron member having an inturned flange resting on the outer shell of said range, said member having a flat top and an integral upturned back piece, said top having an opening therein over said combustion chamber surrounded by an inturned shoulder, an insert adapted to rest on said shoulder in said opening and having stove lid openings therein, a concentrator member disposed over said combustion chamber to cover the latter, said concentrator having a plurality of spaced upwardly tapered and opening concentrator domes disposed in vertical alinement with the respective openings in said insert, insulating material surrounding said domes and insulating the same from one another and the rest of the range, stove lid holders telescopingly received by said domes and engaging said insert around said openings therein, and stove lids disposed in said holders and covering said domes.

3. In a range having an open top combustion chamber, a top having an opening therein, a cast iron insert, means to support said insert in said opening, said insert having stove lid openings therein, a cast iron concentrator member, means for supporting the same on said combustion chamber to cover the latter, said concentrator having a plurality of spaced upwardly tapered and opening concentrator domes disposed in vertical alinement with the respective openings in said insert, insulating material surrounding said domes and insulating the same from one another and the rest of the range, stove lid holders telescopingly received by said domes, and stove lids disposed in said holders to cover said domes.

4. In a range having an open top combustion chamber, a top having an opening therein, an iron insert, means to support said insert in said opening, said insert having stove lid openings therein, a concentrator member, means for supporting the same on said combustion chamber to cover the latter, said concentrator having a plurality of spaced upwardly tapered and opening concentrator domes disposed in vertical alinement with the respective openings in said insert, stove lid holders disposed in concentric relation to said insert openings and engaging the insert, and stove lids disposed in said holders to cover said domes.

5. In a kitchen range having a plurality of stove lids and a combustion chamber beneath said lids having a heating unit therein, means for concentrating heat from the said unit on said respective lids, comprising a cast iron concentrator

- member adapted to rest on and cover said combustion chamber, said member having a plurality of spaced upwardly opening and tapered concentrator domes extending into proximity with said lids, a one-piece vitreous enameled sheet metal top for said range having an opening above said concentrator member, and an insert disposed in said opening and provided with openings in alignment with said domes to receive holders for said stove lids, said holders engaging said domes and supporting the stove lids thereover, there being insulating material disposed between said domes and the remainder of the range to minimize heat conduction and radiation from the domes.
6. In a kitchen range having a plurality of stove lids and a combustion chamber beneath said lids having a heating unit therein, means for concentrating heat from the said unit on said respective lids, comprising a cast iron concentrator member adapted to rest on and cover said combustion chamber, said member having a plurality of spaced upwardly opening concentrator domes extending into proximity with said lids, a top for said range having an opening above said concentrator member, and an insert disposed in said opening and provided with openings in alignment with said domes to receive holders for said stove lids, said holders engaging said domes and supporting the stove lids thereover, there being insulating material disposed between said domes and the remainder of the range to minimize heat conduction and radiation from the domes.
7. In a kitchen range having a plurality of stove lids and a combustion chamber beneath said lids having a heating unit therein, means for concentrating heat from the said unit on said respective lids, comprising a cast iron concentrator member adapted to rest on and cover said combustion chamber, said member having a plurality of spaced upwardly opening concentrator domes extending into proximity with said lids, a top for said range having an opening above said concentrator member, and an insert disposed in said opening and provided with openings in alignment with said domes to receive holders for said stove lids, said holders engaging said domes and supporting the stove lids thereover.
8. In a kitchen range having a plurality of stove lids and a combustion chamber beneath said lids having a heating unit therein, means for concentrating heat from the said unit on said respective lids, comprising a cast iron concentrator member adapted to rest on and cover said combustion chamber, said member having a plurality of spaced upwardly opening concentrator domes extending into proximity with said lids, a top for said range having an opening above said concentrator member, and an insert disposed in said opening and provided with openings in alignment with said domes to receive said stove lids, and means to support said lids over said domes.
9. A kitchen range having a plurality of stove lids and a combustion chamber beneath said lids and having a heating unit therein, means for concentrating heat from the said unit on said respective lids, comprising a concentrator member adapted to rest on and cover said combustion chamber, said member having a plurality of upwardly opening concentrator domes, said range having a top provided with an opening above said concentrator member, and means to support said stove lids in said opening in vertical alignment with said domes.
10. In a range having a combustion chamber, a top for the range having an opening above said combustion chamber, an insert disposed in said opening having openings therein, a concentrator member, and means for supporting the same on said combustion chamber to cover the latter, said concentrator having a plurality of spaced upwardly opening concentrator domes disposed in vertical alignment with the respective openings in said insert whereby to concentrate heat from said combustion chamber at said openings.
11. In a range having a combustion chamber, a top for the range having openings therein, a concentrator member, and means for supporting the same on said combustion chamber to cover the latter, said concentrator having a plurality of spaced upwardly opening concentrator domes disposed in vertical alignment with the respective openings in said top whereby to concentrate heat from said combustion chamber at said openings.

EDWIN ESSON.
